UNITED STATES PATENT OFFICE

2,642,769

ERYTHROCYTOMETER

Robert P. Moore, Hampden-Sydney, Va.

Application June 7, 1950, Serial No. 166,667

5 Claims. (Cl. 88—14)

1

This invention relates to an erythrocytometer, the primary object of which is to permit rapid and easy measurement of the mean diameter of red blood cells prepared as a smear on a microscope slide. The present device is based on a novel extension of the principle that the diameter of concentric spectra produced by the passage of light from a point source through a film of red blood cells is inversely proportional to the mean diameter of the red cells.

Although skilled hematologists can roughly estimate cell diameter by microscopic examination of a blood smear, there is a need in the art for a simple device by which the clinician in office and rural practice may have ready access to the advantage of such measurements, and to this end the present novel erythrocytometer has been conceived and constructed.

Instruments previously devised for this purpose have, by nature of their structure, been poorly adapted for use in office and rural practice; for example, the heretofore known diffractometric direct reading erythrocytometer is too large to carry in a handbag and too expensive for general use outside of a laboratory. The diffraction erythrocytometer approaches the desired simplicity to some extent, but is mechanically undesirable because two variable factors enter into the diffraction changes, thus making calibration a difficult procedure. The present device has been provided to avoid the undesirable features of both of these instruments.

The value of knowing the average red cell diameter is well known to the physician. It is of great aid in the morphological classification, diagnosis and treatment of anemias. For example, the most characteristic feature of Addison's anemia is an increased mean corpuscular diameter, whereas other findings are less constant. Furthermore, the average practitioner is enabled to differentiate the macrocytic group of anemias which are generally amenable to liver therapy from the more common hypochromic anemias which respond generally to iron therapy. Therefore, the present device gives immediate information as to the general diagnosis and pursuit of treatment in the more common anemias, which is not ordinarily possible without the aid of laboratory service. Since the average physician, especially in rural areas, does not have easy access to precise laboratory assistance, this instrument, because of its simplicity and ease of operation, is of great value to the average physician.

These, together with various ancillary objects and features of the invention which will later become apparent as the following description proceeds, are attained by the device, a preferred embodiment of which has been illustrated, by way of example only, in the accompanying drawings, wherein:

2

Figure 1 is a sectional view taken substantially on the plane of section line 1—1 of Figure 2;

Figure 2 is an elevational view of the lower end of the device as shown in Figure 1;

Figure 3 is a sectional view taken substantially on the plane of section line 3—3 of Figure 1;

Figure 4 is a fragmentary sectional view taken substantially on the plane of section line 4—4 of Figure 3;

Figure 5 is a perspective view of a detail of construction.

Specific reference will now be made to the drawings. In the several views, in the accompanying drawings and in the following specification, similar reference characters indicate corresponding elements throughout.

The present erythrocytometer is fabricated of a light-tight box 10 which is elongated and preferably rectangular, although other shapes may be employed. The conventional microscope slide box has been employed to advantage and comprises a base member 12 connected to side members 14, a front wall 16, and a rear wall 18. The upper free edges of the walls are provided with a peripheral recess 20 for seating a removable lid 22 to provide a light-tight box and to allow for access to the interior thereof. The side walls 14 are provided with a pair of transversely aligned, longitudinally spaced serrations or bars 24 at the central portions thereof for receiving microscope slides 26 having blood smears or stains thereon. Thus, the smeared slide 26 is maintained at a constant position in the light-tight box between the ends 16 and 18 thereof.

The rear end 18 of the box is provided with a viewing aperture 28, whereas the forward end 16 of the box is provided with a transversely extending channel 30 for sliding receiving a bar 32 having sloping longitudinal sides 34 to retain the bar within the guide channel 30. Adjacent one end of the bar 32 is a relatively small aperture 36 having an index 38 thereat, this aperture serving as a light receiving aperture. The guide channel 30 and the slidable bar 32 have been provided so that the light receiving aperture 36 can be adjusted transversely of the light-tight box 10 to properly align the aperture 36 with the blood smear on the microscope slide 26.

The slide bar 32 is further provided with an elongated slot 40 adjacent the light receiving aperture 36. A disk 42 is provided which is circular and through the center of which extends a headed pin 44 which in turn extends through a suitable aperture 46 in the slide bar and also extends through a transversely extending slot 48. The slot 48 is provided in the front end 16 of the box and is communicative with a portion of the guide channel 30, as shown clearly in Figure 2. The pin mounting of the disk 42 on the slide bar 32 permits the disk to be rotatable

on the slide bar and also movable transversely with the slide bar.

The disk is provided with calibrations 50 in micra adjacent its peripheral edge and is further provided with a series of apertures of variable transverse distance from the light receiving aperture 36. This series of apertures may be in the form of a continuous slot in the shape of an Archimedean spiral, or preferably, as shown in the drawings, of a series of apertures 52 arranged in the form of an Archimedean spiral, the apertures 52 being selectively positionable in front of the elongated slot 40 of the slide bar 32, as shown clearly in Figures 2 and 3. Inasmuch as the slot 40 in the slide bar 32 is linear and the series of apertures 52 or slot thru the rotatable disk 42 is arranged in an Archimedean spiral, it will be seen that the transverse distance between the light receiving aperture 36 and the spiral slot or spirally arranged apertures 52 may be varied with the rotation of the disk 42. In proportion to the other box dimensions, the light apertures 36 and 52 should be approximately $\frac{1}{16}$ to $\frac{5}{64}$ of an inch in diameter.

In practical operation, to examine blood, a thin unstained smear prepared on a microscope slide is placed in appropriately adjusted position within the box 10 and the lid 22 replaced. When the forward end 16 is held up toward a suitable source of light, one observes, on looking through the viewing aperture 28, a pair of adjacent halo-spectra. One of the pair of halo-spectra is produced by light passing through the fixed aperture 36 and the other is produced by light passing through the movable aperture produced by means of positioning one of the apertures 52 in front of the slot 40. With a properly made smear, one sees that each spectrum has a large central zone of bright light, pale violet in color, which is surrounded by a thin zone of pale yellow merging into dark yellow, and then successive zones of red-brown and blue. A measurement is made by bringing these two halo-spectra into a predetermined position; namely, the tangential approximation of the innermost dark yellow spectra. The value for the average diameter of the red blood cells is then read directly from the calibrations 50 upon the disk coinciding with the index 38. In selecting a light source, one should preferably use a fluorescent type of bulb or any other diffused light which is sufficiently intense. As will be readily understood by those skilled in the art, the sliding bar 32 is used to move the light apertures to the best portion of the smear on the microscope slide 26.

In view of the foregoing description taken in conjunction with the accompanying drawings, it is believed that a clear understanding of the device will be quite apparent to those skilled in this art. A more detailed description is accordingly deemed unnecessary.

It is to be understood, however, that even though there is herein shown and described a preferred embodiment of the invention, the same is susceptible to certain changes fully comprehended by the spirit of the invention as herein described and within the scope of the appended claims.

Having described the invention, what is claimed as new is:

1. An erythrocytometer comprising an elongated light-tight box having a removable lid, one end of said box having a viewing aperture and the other end having a stationary light-receiving

aperture, means for retaining a blood-smeared slide in said box at a constant position between said apertures, a linear slot in said other end terminating adjacent said stationary aperture, an index on said other end proximate said stationary aperture, and a disk having a graduated scale thereon rotatably mounted on said other end and including a plurality of apertures arranged in an Archimedean spiral, said disk apertures being selectively positionable in front of said linear slot.

2. The combination of claim 1 wherein said other end of said box includes a transversely slideable member, said stationary aperture and said linear slot being provided in said slideable member and said rotatable disk being mounted on said slideable member.

3. An erythrocytometer comprising an elongated substantially light tight housing, a viewing aperture at one end of the housing, a transverse slot in the opposite end of the housing, a slide support intermediate the ends of the housing for holding a blood smeared slide transversely in the line of sight between said aperture and said slot, a bar overlying said slot in light tight relation, a light receiving aperture in said bar, said light receiving aperture being adjustable along said slot, a slot in said bar, a disk covering the slot in said bar, a spiral row of apertures in said disk, said apertures being selectively registrable with said slot in said bar.

4. An erythrocytometer comprising an elongated substantially light tight housing, a viewing aperture at one end of the housing, a transverse slot in the opposite end of the housing, a slide support intermediate the ends of the housing for holding a blood smeared slide transversely in the line of sight between said aperture and said slot, a bar overlying said slot in light tight relation, a light receiving aperture in said bar, said light receiving aperture being adjustable along said slot, a slot in said bar, a disk covering the slot in said bar, a spiral row of apertures in said disk, said apertures being selectively registrable with said slot in said bar, a guide channel receiving said bar.

5. An erythrocytometer comprising a light tight box, a viewing aperture at one end of said box, a guide channel in the outer surface at the opposite end of the box, a slot in said end said slot communicating with said channel, a slide bar positioned in said channel, a fixed light receiving aperture in said bar, a longitudinal slot in said slide bar, a disk pivotally mounted on said slide bar, a row of apertures in said disk said apertures being arranged in spiral formation, said apertures being selectively registrable with said slot in said slide bar, a slide holder intermediate the ends of said box.
